ABSTRACT OF THE DISCLOSURE

A variable resistance circuit includes a pair of transistors, each having an emitter load resistor, and a pair of diodes serially connected between the emitters of the transistors. Input signal applied to the transistor controls the variable resistance which appears between the common connection of the diodes and a reference terminal but does not appear between these terminals.

This invention relates to a variable resistor circuit using semiconductor diodes and has as its principal object the provision of a circuit in which the dynamic resistance can be controlled by an electric signal.

It is another object of the present invention to provide a variable resistance circuit which decreases signal distortion due to the nonlinear, signal-controlled conductive characteristics of semiconductor diodes.

Other and incidental objects of the present invention will be apparent from a reading of this specification and an inspection of the accompanying drawing in which:

FIGURE 1 is a circuit diagram of one embodiment of the present invention;

FIGURES 2 and 4 are circuit diagrams of preferred embodiments of the present invention; and

FIGURE 3 is a graph showing the characteristic operation of this invention.

FIGURE 1 shows the fundamental circuit of this invention. D_1 is a junction type semiconductor diode, Q_1 denotes a transistor, R_1 and R_2 represent resistor elements whose resistance values are represented by symbols R_1 and R_2 in the diagram respectively. Assuming that i_{D1} is the forward current of semiconductor diode D_1 , and i_{E1} is the emitter current of transistor Q_1 , the equivalent resistance R_{D1} presented to small amplitude input signals as seen from terminals 1 and 2 is given as the sum of the dynamic resistance of diode D_1 and the parallel resistance of R_2 and the equivalent resistance as seen from the emitter side of Q_1 .

This can be expressed by the following formula:

$$R_{D1} = 1/\frac{q}{kT}(i_{D1} + i_{S1}) + R_2 \parallel (1/\frac{q}{kT}i_{E1} + R_1/h_{fe1}) \quad (1)$$

In Formula 1, i_{S1} represents the backward saturation current (unit ampere) of diode D_1 , h_{fe1} represents the current amplification factor of transistor Q_1 , and the second term of the right side represents the parallel resistance of R_2 and the equivalent resistance as seen from the emitter side of transistor Q_1 .

Thus, by setting i_{E1} fairly large as compared with i_{D1} , selecting a large h_{fe1} for transistor Q_1 , and by setting a small value for

$$R_1, R_2 \parallel (1/\frac{q}{kT}i_{E1} + R_1/h_{fe1})$$

can be materially disregarded in relation to

$$1/\frac{q}{kT}(i_{D1} + i_{S1})$$

Therefore, the following formula will become valid:

$$R_{D1} \cong 1/\frac{q}{kT}(i_{D1} + i_{S1}) \quad (2)$$

5 Regarding the probable resistance value for R_{D1} from Equation 2, if $T = 290^\circ$ K., $q/kT = 40$ v.⁻¹, and

$$R_{D1} = \frac{1}{40}(i_{D1} + i_{S1})$$

then so long as $i_{D1} \gg i_{S1}$ is valid, $R_{D1} \cong \frac{1}{40}i_{D1}$ and therefore $R_{D1} \cong 250\Omega$ at $i_{D1} = 10^{-4}$ A. (100 μ A.), and $R_{D1} \cong 25\Omega$ at $i_{D1} = 10^{-3}$ A. (1 ma.). On the other hand, if a backward voltage is applied to the diode, and $i_{D1} \rightarrow i_{S1}$ is caused, then $R_{D1} \rightarrow \infty\Omega$.

The circuit of FIGURE 2 consists of two of the basic circuit shown in FIGURE 1 connected by input terminal 1 and 2, with the driving power source commonly connected. Here, it is assumed that transistors Q_1 and Q_2 are of equal characteristics, that R_2 and R_3 are equal, and that diodes D_1 and D_2 are also of equal characteristics. In the case where control signal currents I_{B1} and I_{B2} whose magnitudes are mutually different are supplied from external sources to terminals 7, 8 and to terminals 9, 10 and current I_D flows at diodes D_1 and D_2 , the equivalent resistance R_D as seen from terminals 1 and 2 can be approximated by

$$\frac{q/kT + (I_D + I_S)}{2}$$

30 This is illustrated in FIGURE 3 in which the horizontal axis represents voltage and the voltage between points O_1 and O_2 is the voltage across the serially-connected diodes D_1 and D_2 . Curve (a) represents the voltage-current characteristic curve of D_1 , curve (b) represents the characteristic curve of D_2 , and curve (c) represents the resultant characteristic curve of D_1 and D_2 . The gradient of the tangential line on curve (c) at its point of intersection with the horizontal axis gives

$$\frac{1/\frac{q}{kT}(I_D + I_S)}{2}$$

35 The nonlinear distortion is much improved in the circuit of FIGURE 2 compared with that of FIGURE 1. The even number higher harmonic distortion can be completely removed if the characteristics of D_1 and D_2 are identical.

40 In the circuit of FIGURE 2, transistors Q_1 and Q_2 are of identical characteristics, but Q_1 and Q_2 may be made complementary pair transistors and a control signal may be applied between terminals 7 and 9. In this case, however, should one transistor Q_1 be of P-N-P type, for instance, the collector of Q_1 must be connected to a power source terminal of negative polarity instead of to a power supply terminal of $+E_v$ volts, as shown.

45 FIGURE 4 shows an actual connection diagram for regulating the equivalent resistance between terminals 1 and 2 by a control signal (DC) applied to terminals 15 and 16. Terminal 15 is connected to the base of transistor Q_3 through resistor R_5 . The collector of transistor Q_3 is connected to power source terminal $+E$ through resistor R_4 , and its emitter is connected to reference potential line G through resistor R_1 . Also, the two electrodes collector and emitter of Q_3 are bridged by semiconductor diodes D_3 and D_4 ; emitter electrode 7 is connected to the base electrode of transistor Q_1 ; and collector electrode 9 is connected to the base electrode of transistor Q_2 . Other connections are identical with those of the circuit of FIGURE 2 and the related descriptions are omitted for brevity.

50 In FIGURE 4, emitter current I_{E3} of transistor Q_3 in-

3

creases or decreases in accordance with the magnitude of the control signal applied to terminals 15 and 16; but when current amplification factor h_{fe3} of Q_3 is sufficiently great, collector current I_{C3} is always approximately equal to I_{E3} ; and, assuming that R_1 equals R_4 , inter-terminal voltage $E_1=R_1I_{E3}$ across R_1 will be always approximately equal to inter-terminal voltage $E_3=R_4I_{C3}$ across R_4 . Thus, the following equation is valid for the voltage E_2 appearing between the base of Q_2 and reference potential line G:

$$E_2=E-E_3=E-E_1 \quad (3) \quad 10$$

Here, E denotes the driving power source voltage to reference potential line G.

Now, if we assume that voltage E_{BE1} between the base and emitter of Q_1 is always approximately equal to voltage E_{BE2} between the base and emitter of Q_2 within the operating range of this circuit (I_D should not be made large so that I_{E1} will not appear negligibly small compared with I_{E2} , and so that the difference between E_{BE1} and E_{BE2} will not appear conspicuously large.), then: 15 20

$$E_4=E_1-E_{BE1}, \quad E_5=E_2-E_{BE2} \approx E-E_1 \\ -E_{BE2} \approx E-E_1-E_{BE1} \quad (4)$$

When the characteristics of diodes D_1 and D_2 are equal, voltage E_6 at node 1 of D_1 and D_2 can be given by the 25 means value of E_4 and E_5 . Therefore:

$$E_6=\frac{(E_4+E_5)}{2}=\frac{(E-2E_{BE1})}{2} \quad (5)$$

and it is a constant voltage that has no relation to the 30 control input (viz, this indicates the high degree of isolation between the control signal and the controlled circuitry) which prevents the control signal from appearing between terminals 1 and 2.

The voltage applied to the series circuit of diodes D_1 35 and D_2 in the forward direction of these diodes may be expressed as follows:

$$E_5-E_4 \approx E_2-E_1=E-2E_1$$

This voltage is approximately equal to the voltage between 40 the collector and emitter of transistor Q_3 . The minimum possible value for the collector-emitter voltage of Q_3 occurs when Q_3 is saturated ON, and the maximum value occurs when Q_3 is OFF, and the voltage applied to the 45 series circuit of D_3 and D_4 is produced by the current that flows through R_4 , D_3 , D_4 and R_1 in the direction of the order named. This current in the series circuit of diodes D_3 and D_4 can be set at an arbitrary value when driving 50 voltage E is constant by changing the values of resistance R_1 and R_4 . Also, assuming that diodes D_3 and D_4 are identical to D_1 and D_2 , as the current in the series circuit of D_1 and D_2 is approximately equal to the current in the series circuit of D_3 and D_4 , the maximum value of current I_D that flows in diodes D_1 and D_2 , consequently the minimum possible value of R_D , can be set arbitrarily by selecting the values of R_1 and R_2 . 55

In the variable resistance circuit of this invention, non-linear distortion is negligibly small on low level AC signals, and the equivalent resistance as seen from the input of the circuit can be controlled by the DC control signal. Moreover, the embodiment of the invention illustrated in FIGURE 4 provides high isolation of the control signal from the input circuitry and provides a minimum value of variable resistance R_D at the input terminal which can be arbitrarily controlled so that the present invention can be used very effectively as a variable resistance element in an automatic balancing bridge.

I claim:

1. A variable resistance circuit comprising:
a source of reference potential;
a pair of transistors, each having base, emitter and collector electrodes and being connected in emitter-follower circuits, each including a load resistance connected between an emitter electrode and said source of reference potential;
a series circuit including a pair of diodes serially-connected in unidirectional conduction alignment between the connection of the emitter electrode and the load resistance of each of said emitter-follower circuits;
control input means connected to said pair of transistors for applying a control signal to each of the input bases of the transistors connected in emitter-follower circuits; and
a pair of circuit terminals, one circuit terminal being connected to said series circuit intermediate said pair of diodes and the other circuit terminal being connected to said source of reference potential, whereby the resistance between said pair of circuit terminals is varied in response to signal applied to said control input means.

2. A variable resistance circuit as in claim 1 wherein said control input means includes a control transistor having a load resistance connected to the emitter and another resistance connected to the collector;

means connecting the bases of said pair of transistors to the collector and emitter of said control transistor; and

diode means connected between the bases of said pair of transistors.
